SURFACE COVERING ELEMENT

Herbert G. Goslin, Augusta, Mich., assignor to
 Sheriff-Goslin Co., Battle Creek, Mich., a corporation of Michigan

Application January 7, 1947, Serial No. 720,622

4 Claims. (Cl. 108—7)

1

The present invention relates broadly to surface covering elements, and in its specific phases to relatively rigid shingles suitable for use as roofing or siding elements.

Asbestos-cement shingles which have a cement binder and are hard, relatively rigid, moderately resilient surface covering elements, have come into wide-spread use as roofing, and more recently they have been adapted to use as siding. While asphalt shingles sometimes have asbestos fibres in them, these shingles are made of flexible stock which is rollable and may be cut to size as it continuously comes from the manufacturing apparatus, thus avoiding cutting waste, and utilizing a manufacturing procedure which is not adapted to asbestos-cement shingles. In the case of the latter the stock is commonly made in 24" x 24" panels from which the shingles themselves are cut. In using these panels, the shingles may be cut in rectangular shape to form two shingles without waste, but when laid in normal manner, the maximum exposure is six inches and beyond which there is no underlap for the side joints between shingles. In fact, considerably less than six inches of exposure must be used if leakage at the side joints is to be avoided by the shingles alone, even with siding where vertical laying is involved. The overcoming of this difficulty with maintenance of relatively wider exposures has been accomplished in the past by using narrow strips of tar paper or roll roofing under the side joints between shingles. One way to avoid this need of understripping has been to cut the shingles with upward projecting tabs adapted to underlie the side joints. This in turn raises the problem of how to make all shingles uniform in size and shape, and at the same time avoid waste in cutting from the 24" x 24" panels. In my U. S. Patent No. 2,115,222, I set forth a tabbed shingle construction wherein four shingles were cut from a single panel of stock. Of these shingles two had long tabs and two had short tabs for use in laying in alternating wide and narrow exposure courses. The present invention is a modification of that invention coupled with other elements which produce a new combination having entirely new capabilities.

Asbestos-cement shingles of present day designs are also prone to work loose and rattle, and to avoid this it has become rather common practice to use exposed stainless steel nails, or cadmium coated bronze nails to anchor the lower edge of the shingles in place. Since it is almost impossible to drive a nail through an unpunched

2

asbestos shingle without either breaking the shingle or bending the nail, this in turn has required either nailing above the head lap or punching a second set of matching holes in the shingles to facilitate driving the nails simultaneously through both the bottom holes in the top course of shingles and these corresponding holes in the top of the underlying lower course of shingles. The exposed extra nails thus used are relatively expensive and these exposed nail holes must be calked if leakage is to be avoided. It was a recognition of these and other problems and difficulties in the surface covering art which led to the conception and development of the present invention.

Accordingly, among the objects of the present invention is the provision of a way to cut identical size shingles, each having a multiple tabbed edge, from a rectangular blank without cutting waste.

Another object is to provide a sheet with multiple curves such that when cut with tabs down the center, the resultant shingles will be of identical size, and when nailed in place on a flat surface, with the nails at points high enough up the shingle to be covered a short distance by the next higher course of shingles, the curvature will be flattened to a certain extent, and the butt edge of the shingle forcibly held against the next lower course of shingles, thus resiliently avoiding loosening and rattling, all without the need of exposed nailing.

Another object is to provide inverse curved relatively rigid shingles having a straight lower edge, the curves facilitating nesting for shipping as well as when laid, avoiding loosening and rattling in use, and wherein the upper edge slides runner fashion on the roofing paper commonly used under asbestos shingles, thus avoiding injury to the paper which might otherwise occur during nailing of the shingles.

Another object is to provide relatively rigid but resilient shingles which may be laid with greater exposure than usual, and thus cost less per square to lay, while having tabs for use in underlapping the side joints of the next higher course of shingles when laid in conventional manner.

Another object is to cut a pair of relatively rigid but resilient shingles from a rectangular blank which has two longitudinal convex curves joined by a concave curve, said convex curves being parallel and in the butt edge portion of each shingle, whereby the butt edge will be bound against the next lower course of shingles when

the former is anchored with nails which are normally high enough to be covered a short distance by the next higher course of shingles.

A further object is to provide the shingles with multiple tabs having sloping side edges wherein one end of the shingle passes approximately through the center of the sloping edge of one of the tabs, while the other end of the same shingle starts with a piece of tab the size of that missing from the edge of the tab at the opposite end of the shingle.

Still further objects and advantages will appear as the description proceeds.

To the accomplishment of the foregoing and related ends, the invention, then, consists of the means hereinafter fully described and particularly pointed out in the claims, the annexed drawing and the following description setting forth in detail certain means for carrying out the invention, such disclosed means illustrating, however, but one of the various ways in which the principle of the invention may be used.

In the annexed drawing:

Figure 1 shows a rectangular piece of shingle stock with a preferred tab cutting line shown.

Figure 2 shows an edge view of a preferred form of the shingle blank illustrated in Figure 1.

Figure 3 shows an edge view as seen from the right hand side of Figure 4.

Figure 4 shows an assembly view of three shingles of the present invention laid in conventional manner.

Referring more particularly to Figures 1 and 2 of the drawing, it will be noted that a standard size 24" x 24" shingle blank 1 has been shown cut down its center to form two substantially equal size shingles 2, each of which is two shingle units long, although the same shingle may be cut with more than two shingle units, for instance, by cutting it with the equivalent of three full tabs and three hollows, a three unit length shingle will be formed, and it is intended that the showing be considered as diagrammatically illustrating same. Each of the shingles illustrated has one full size tab 3, while the second tab 3a terminates in a line perpendicular to the base of the shingle at approximately the mid-point of the tab's sloping edge furthest from full size tab 3. Partial tab 3b at the opposite edge of the shingle is approximately the same size as the portion missing from the side of tab 3a and which would make it full size the same as tab 3. Thus the full tab 3 and the partial tabs 3a and 3b together with the two full size hollows therebetween produce a shingle of two unit lengths, while the 24" x 24" blank produces two such shingles. These shingles may be made from any suitable shingle stock which is relatively rigid and yet resilient, such as asbestos-cement, and plastics, as well as some types of glass and ceramics.

The particular method of making the shingles of the present invention will depend considerably upon the particular type of material to be used. For instance, if the shingles are to be made from plastic, the panels may be either extruded or molded with the curvature in place as shown in Figure 2, while if the shingles are to be made from asbestos-cement, the panel will be molded and allowed to harden before removal from the mold. In the case of glass, they could be either molded or formed on a suitable curved surface, following which the panel would be allowed to cool and thus harden before removal. The panels in any case may be made either to finished size,

or they may be made a little larger than finished size, and then trimmed as well as cut to form the multiple tabs on the shingles.

Asbestos-cement shingles have always given trouble due to loosening and rattling in use, and to avoid that situation, which is especially prevalent when that type of shingle is used as siding, it has become common practice to perforate the shingle along its bottom edge for nails and to also suitably perforate it at higher elevations, so that when nailed to a wall, the bottom perforations of one shingle will match the upper perforations of the lower shingle in manner such that a nail or nails can be driven therethrough. In order to avoid this exposed nailing entirely, the shingle blank as shown in edge view in Figure 2, is preformed with two convex curves 5 and 6 in its butt edges, and these two curves in turn are preferably joined by a concave curve 7. While the size of the convex curves may be varied over a considerable range, it has been found that if the convex curves on the under face of the blank rise approximately three-eighths of an inch above a plane joining the edges and center of the under face of the conventional thickness asbestos shingle blank, this will meet practically all requirements, although it may be varied from this to meet varying thicknesses of blanks as well as varying compositions which have different amounts of resiliency, all without departing from the spirit of the invention.

Two sets of nail holes are provided in each shingle, which is two units long, preferably at the locations typically illustrated in Figure 4. These nail holes are at an elevation such that when the shingle is nailed in place and the next higher course nailed thereover, the nails 4 in these nail holes will be completely covered. This makes it possible to use ordinary cheap galvanized iron nails rather than having to resort to either stainless steel or cadmium coated bronze nails which have to be used at the present time in order to avoid weathering stains eventually appearing below each nail. Even with the cadmium coated nails, the cadmium wears off in time and the bronze head of each of the nails shows black, thus resulting in an unsightly appearance. These nail holes at the same time are so located as to permit the nails to be driven between tabs of the lower course of shingles. With the nail holes placed as shown in Figure 4, shingles made from a 24" x 24" blank can have a 7" exposure when laid, and this may be reduced to 5" without difficulty. The curvature of the individual shingles is also such that when the nails are driven, they will slightly flatten the convex curve 5 (or 6) in the butt of the shingle and thus resiliently hold the shingle tightly in nested, non-rattling position. Figure 3 shows the overlying individual shingles, as laid, from which it may be observed that, while the butt edge of each shingle curves down toward the next lower shingle, the upper edge of the shingle curves upward, facilitating upward sliding of this edge during nailing. At the same time the upper edge of the shingle fits under the downcurving butt of the next higher shingle, thus producing a relatively tight-fitting resiliently held superimposed set of shingle courses.

How the shingles actually appear when laid is typically illustrated in Figure 4, from which it will be noted that the joints between shingles in one course may be laid so as to come at the center of a full size tab 3, thus again making an exceptionally tight and leak resistant assembly suit-

able for either roofing or siding. When a wall of this type of wide exposure shingles is laid up, it is exceptionally attractive and very closely simulates the pleasing appearance of the old style siding which has long been known as clapboard siding.

Other modes of applying the principle of my invention may be employed instead of those explained, change being made as regards the means herein disclosed, provided those stated by any of the following claims or their equivalent be employed.

I, therefore, particularly point out and distinctly claim as my invention:

1. A surface covering element, comprising a shingle having a tabbed upper edge and a relatively straight butt edge, said shingle having in vertical section extending from the butt edge to the top of said tabbed edge a relatively shallow convex curved portion starting at the butt edge portion thereof and continuing into a relatively shallow concave curved portion terminating in the tabbed edge thereof.

2. A surface covering element, comprising a shingle having a tabbed upper edge and a relatively straight butt edge, said shingle having in vertical section extending from the butt edge to the top of said tabbed edge a relatively shallow convex curved portion starting at the butt edge portion thereof and continuing into a relatively shallow concave curved portion terminating in the tabbed edge thereof, said tabbed edge having wide-base narrow-top tabs with at least one sloping side, there being at least one full size tab with one end of the shingle terminating substantially at the midpoint of a sloping side of another tab, and the other end of the shingle terminating with a partial tab of approximately the same size as the missing portion of the tab at the other end of the shingle.

3. In a surface covering material adapted to be laid so as to simulate clapboard siding, the combination which includes a plurality of substantially rectangular elements of the same size laid in superimposed overlapping relation, each of said elements having a tabbed upper edge with at least one full size tab and two partial tabs with a full size hollow between tabs, each of said tabs having a wide base and a narrow top with oppositely sloping side edges, said element terminating at one end approximately at the mid-

point of the sloping edge of a tab and at the other end with a partial tab approximately the same size as the missing portion of the tab at the other end of the element, the butt edge of each element being relatively straight and having in vertical section extending from the butt edge to the top of said tabbed edge a relatively shallow convex curved portion starting at that edge and continuing into a relatively shallow concave curved portion terminating in the tabbed edge.

4. A surface covering comprising a plurality of substantially rectangular tabbed elements of the same size laid in superimposed overlapping relation, the tabbed upper edge of each of said elements having at least one full size tab and two partial tabs with a full size hollow between tabs, each of said tabs having a wide base and a narrow top with oppositely sloping side edges, said element terminating at one end approximately at the midpoint of the sloping edge of a tab and at the other end with a partial tab approximately the same size as the missing portion of the tab at the other end of the element, the butt edge of each element being relatively straight and having in vertical section extending from the butt edge to the top of said tabbed edge a relatively shallow convex curved portion starting at that edge and continuing into a relatively shallow concave curved portion terminating in the tabbed edge, said elements being laid with their abutting side edges substantially centered on full size tabs of the underlying course of elements, each element being perforated for nailing under and a little above the lower edge of the next higher course of elements, and between the tabs of the next lower course of elements.
